UNITED STATES PATENT OFFICE.

EDWIN A. WEBSTER, OF PLAISTOW, NEW HAMPSHIRE, ASSIGNEE TO UNITED SHOE MACHINERY COMPANY, OF PATERSON, NEW JERSEY, A CORPORATION OF NEW JERSEY.

SOLE-SPLITTING MACHINE.

1,225,900.

Specification of Letters Patent. Patented May 15, 1917.

Application filed September 7, 1915. Serial No. 49,205.

To all whom it may concern:

Be it known that I, EDWIN A. WEBSTER, a citizen of the United States, residing at Plaistow, in the county of Rockingham and 5 State of New Hampshire, have invented an Improvement in Sole-Splitting Machines, of which the following is a specification.

This invention relates to machines for splitting the heel-portion of the soles of 10 shoes, so that a thin tongue, or flap may be turned up from the grain side of the leather to cover the breast-portion of a wood heel.

In machines of this character it is customary to provide a bed having a flat, corrugated, sole-supporting surface and a splitting knife which is disposed in parallel relation to said surface, and transversely thereof, together with means for causing the bed or the knife to be moved reciprocally, 20 one with relation to the other, to split off the tongue from the heel of the sole.

In the particular machine illustrated, and in which my invention is embodied, the splitting knife is held stationary and the 25 bed is reciprocated therebeneath, but it is not essential to my invention whether the bed or the knife be reciprocated.

In machines of this character the sole is pressed onto the bed, so that it will not 30 be moved out of position thereon, by various means, common forms being a presser roll or a presser bar which bears on the sole in advance of the knife edge.

Machines of this character frequently perform 35 their work unsatisfactorily for the reason that the flap, which is split off, is not of uniform thickness, or is unduly stretched, or is torn off, damage of this sort frequently rendering the sole unfit for use as a sole.

40 Variations in thickness of the flaps, which are split off, are due to various causes, one of which is the variation in the substance, or hardness of different soles, or different portions of the same sole. That is, variations 45 in hardness of the leather will cause variations in the extent to which the knife will dig into the same as the splitting operation proceeds. Moreover, even if there is no substantial variation in hardness, the knife will

50 frequently split off a flap of increasing thickness from the heel end of the sole, as its beveled edge tends to lift the sole more and more from the bed, as it advances, and while

this action may be very gradual, the difference in thickness at the end and at the shank 55 may be varied to a marked degree.

A further difficulty, which is encountered, arises from the tendency of the machine to stretch or tear off the flap on its return motion, or as the sole is carried back beneath 60 the presser gage. To prevent the knife from digging into the sole, or lifting it up at some points more than others, it is necessary to have the presser-gage bear on the sole with considerable force, and as close 65 to the knife edge as practicable, but when this is done, the presser bears with so much force on the sole, during the return motion, that the flap is frequently torn off, or at least stretched out of shape. 70

The object of my invention is to provide a machine of the above described character with means for holding the sole against the bed in such a manner that the flaps, which are split off, will be of uniform thickness 75 throughout, under all conditions, and will not be stretched, torn, or otherwise injured by the machine when the motion of the parts is reversed.

I accomplish this object by providing a 80 form of sole gage which is adapted and arranged to engage and bear sharply on the sole surface in sufficiently close proximity to the knife edge and with sufficient force to prevent the knife from digging into, or 85 lifting up the sole, and thus splitting off a flap which is thicker in some portions than in others, and which is adapted to yield to permit the flap to pass freely between it and the knife, on the return motion of the 90 bed, so that the possibility that the flap will be torn off, or stretched, is obviated.

For a more complete understanding of my invention, reference is made to the accompanying drawing, in which:— 95

Figure 1 is a plan view of the bed portion of a sole-splitting machine embodying my invention.

Figs. 2 and 3 are longitudinal sectional views thereof. 100

Fig. 4 is a front end view.

Fig. 5 is a detail end view of the presser, or sole holding gage.

In the drawing *a* indicates the frame of a sole splitting machine of the type above referred to, *b* the bed, and *c* the splitting 105

knife, said bed having a flat, corrugated, sole-receiving face and having means, as the connecting rod d , for reciprocating the same beneath the knife, between predetermined limits, and at right angles to its cutting edge.

According to my invention a sole-holding gage e is rotatably mounted in lugs f at each side of the guide-ways in which the bed reciprocates, said presser having one or more sole-engaging portions e' , e , either, or any one of which may be employed, and each of which is provided with a curved sole-engaging surface e^2 , which terminates in a face e^3 , disposed in a plane which extends approximately radially with relation to the axis about which the gage swings, and parallel thereto. Said gage is adjusted and arranged in such a position that the edge e^4 , provided at the meeting of the surfaces e^2 , e^3 , is held above and in advance of the cutting edge of the knife, at a distance equal to, or corresponding to the desired thickness of the flap to be split off. A set screw g is mounted in an angle bracket h , in position to engage said gage at a convenient point, as one of the surfaces e^3 , so as to prevent the edge e^4 from being swung rearwardly over the knife, or beyond the position above referred to.

A coiled spring k is arranged about one trunnion of the gage in position to rotate the gage in a direction to cause it to be normally held against said stop-screw g . In practice the bed may be pressed upwardly against the gage e by springs, as i , or the gage and knife may, obviously, be pressed down by spring action.

In operation, the gage e holds the sole firmly in position on the bed, so that its upper surface is firmly held in a predetermined relation to the knife. When thus held, the knife will not lift up the sole or be permitted to dig into it to a greater depth at one point than at another, and, as a result, the flap, which is split off, will be of uniform thickness. On the return motion of the bed, to withdraw the sole, the gage is swung back against the action of the spring k by the friction of the sole thereagainst, so that the edge e^4 is carried back from the knife edge and up from the bed, the space therebetween thus being increased to a sufficient extent to relieve all strain from the flap, and permit it to pass freely therebetween, as shown in Fig. 5. All danger that the flap will be pulled off, stretched or otherwise damaged, is thus avoided, and, as soon as the sole is carried out of contact with the gage, the spring k swings it back to its normal position, or in position to engage the next sole.

When one sole-engaging-portion becomes worn, so that it is uneven, another portion may be moved into position, and, when it is

desired to make all the sole-engaging surfaces level or true, the gage may be placed in a lathe and this work readily accomplished.

I claim:—

1. A sole-splitting machine having a splitting knife and a sole supporting bed, means to reciprocate said knife and bed relatively, a presser gage for holding the sole against the bed in proximity to the knife edge, and means permitting said gage to move out of effective pressing engagement with the sole on the return movement of the reciprocating part.

2. A sole-splitting machine having a splitting knife and a sole supporting bed, means to reciprocate said knife and bed relatively, a presser gage, means for causing said gage to press the sole firmly against the bed in proximity to the knife edge during the forward movement, and means permitting the sole-engaging portion of said gage to move away from the bed and the knife edge on the return movement of the reciprocating part, whereby the pressure of the gage upon the sole is greater during the forward movement than during the return movement.

3. A sole-splitting machine having a splitting knife and a sole-supporting bed, means to reciprocate said knife and bed relatively, a presser-gage having a sole-engaging face normally extending into proximity to the knife edge and terminating abruptly at that point, and means permitting movement of said gage to carry its sole-engaging face away from the knife-edge and the surface of the bed, at the beginning of the return movement of the reciprocating part.

4. A sole-splitting machine having a splitting knife and a sole-supporting bed, means to reciprocate said knife and bed relatively, a presser-gage mounted above the bed to swing about an axis approximately parallel to the knife-edge, and having a curved face arranged to engage the sole in proximity to the knife edge, and recessed over the edge portion of the knife to terminate said face abruptly, and a stop for limiting the swinging movement of said gage toward the knife.

5. A sole-splitting machine having a splitting knife and a sole-supporting bed, means to reciprocate said knife and bed relatively, a presser-gage mounted above the bed to swing about an axis approximately parallel to the knife-edge, and having a curved face arranged to engage the sole in proximity to the knife edge, and recessed over the edge portion of the knife to terminate said face abruptly, a stop for limiting the swinging movement of the gage toward the knife, and means to hold said gage yieldingly in engagement with said stop.

6. A machine of the class described, having, in combination, a stationary knife, a stock supporting bed, means for reciprocating said bed to cause the knife to produce a flap on the stock and then to be withdrawn, a gage for pressing the stock against the bed in advance of the knife, and means for causing the gage to exert a greater pres-

sure upon the stock during the formation of the flap than during the withdrawal.

In testimony whereof, I have signed my name to this specification. 10

EDWIN A. WEBSTER.
